UNITED STATES PATENT OFFICE.

GEORGE B. CLEMMER, OF TRENTON, NEW JERSEY.

DESIGN FOR A CONDIMENT-HOLDER.

43,189.

Specification for Design.

Patented Oct. 29, 1912.

Application filed July 31, 1912. Serial No. 712,568. Term of patent 7 years.

To all whom it may concern:

Be it known that I, GEORGE B. CLEMMER, a citizen of the United States, residing at Trenton, in the county of Mercer and State of New Jersey, have invented a new, original, and ornamental Design for Condiment Holders, of which the following is a specification, reference being had to the accompanying drawing, forming part thereof.

The figure is a perspective view of a condiment holder, showing my new design.

As shown in the drawing the novel holder has a polygonal sided body portion A with vertical faces, said body portion being outwardly flared at bottom as at B, and on its

upper end is a cylindric portion C, above which is a semi-spherical dome portion D.

The prominent features of the design are the polygonal sided body with the flaring base, and the semi-globular dome-like top and the cylindric portion between the base and top or dome.

I claim:

The ornamental design for a condiment holder, as shown and described.

GEORGE B. CLEMMER.

In presence of—

ALBERT HUGHES,
SAMUEL L. CARLISLE.
